UNITED STATES PATENT OFFICE.

CLEMENT SMITH, OF TOPEKA, KANSAS, ASSIGNOR TO C. J. BAKER, OF SAME PLACE.

TYPE-ALIGNER FOR TYPE-WRITING MACHINES.

SPECIFICATION forming part of Letters Patent No. 326,062, dated September 8, 1885.

Application filed May 1, 1884. (No model.)

To all whom it may concern:

Be it known that I, CLEMENT SMITH, a citizen of the United States, residing at Topeka, in the county of Shawnee and State of Kansas, have invented certain new and useful Improvements in Type-Aligners for Type-Writing Machines; and I do declare the following to be a full, clear, and exact description of the invention, such as will enable others skilled in the art to which it appertains to make and use the same, reference being had to the accompanying drawings, and to letters or figures of reference marked thereon, which form a part of this specification.

15 Figure 1 of the drawings is a plan view of my device. Fig. 2 is an end view. Fig. 3 is a vertical section, and Fig. 4 is a detail view.

This invention has relation to type-aligners for writing-machines; and it consists in the 20 construction and novel arrangement of parts, as hereinafter set forth, and pointed out in the appended claims.

In the accompanying drawings, the letter A designates the frame, which, in the construction illustrated, consists of two parallel guide-bars, B B, carrying the adjustable transverse head G, having the downwardly and outwardly turned arms D, and also carrying the adjustable upwardly and outwardly turned 25 arm E.

The arm E, on the horizontal portions of the bars B, is designed, when the aligner is adjusted in position, to press against the rod to which the carriage is attached, or against 30 some other suitable portion of the machine. Set-screws *g g* are inserted in threaded bearings in the arm E, and serve to hold said arm to its position after adjustment by pressing against the bars B B. The arm E can be 35 adjusted forward or backward readily upon the bars B B, so that it is easily fitted to the machine.

The head G rests by its arms D D on the index-bridge or other available part of the type-writing machine. It is provided with 40 bearings *h h*, through which the vertical portions *k k* of the bars B B pass, and it is adjustable up and down on bars. Set-screws *l* are inserted in threaded bearings of the head G, and serve to fix the position of the guide bars 45 or wires B B when adjusted to the proper height on the machine.

The index-bridge of the machine should be provided with small lugs capable of being attached thereto, and serving as a guide to fix the position of the arms of the piece G to 55 prevent the aligner from moving sidewise.

The slide L is an adjustable horizontal plate having bearings *m*, through which the wire guides or bars B pass. This plate is adjustable on the bars B, and is designed to afford 60 a guide to set or align the type of the machine. To this end the plate is provided with an opening, *m'*, within the margin of which extend arms or points *v* and *z*, the former serving to align the top of the letter and the latter its 65 base. In the illustration the back of a piece of wire bent in the form of the letter C forms the upper guide, *v*, and the ends thereof the lower guide, *z*. Another form, showing these guides differently arranged, is illustrated in 70 Fig. 4.

It will be observed that the employment of the guides extending within the opening *m'* of the plate L is to provide not only a sufficient guide for the alignment of the type, but 75 also a stop to engage the face of the type and prevent the same from rising through the opening. In this manner the type are all brought to an ascertained position, so that there will be no variation thereof either in 80 the horizontal plane or vertically after adjustment.

The form of the aligner-frame may be varied to suit the shape of the machine to which it is to be applied. The form illustrated is adapted to the so-called "caligraph" writing-machine.

This aligner is capable of being instantly connected to or detached from the machine. The guides B are held between the head G 90 and the arm E by bracing the same against the abutments of the machine.

Having described this invention, what I claim, and desire to secure by Letters Patent, is—

1. A type-aligner for type-writing machines, having adjustable arms braced against abutments of the machine to hold said aligner in position, substantially as specified.

2. A type-aligner consisting of parallel 100 guide-wires or bars B, an upwardly and outwardly turned arm on the horizontal portions

of said bars, downwardly and outwardly turned arms on the vertical portions of said bars, and the aligning-guide slide engaging said bars, substantially as specified.

- 5 3. The combination, with the parallel bars of a type-aligner, of an adjustable aligning-slide having an opening, m' , and guides by which to fix the position of the type not only in the horizontal plane, but, also vertically, substantially as specified.
- 10 4. A type-aligner having one of its support-

ing-arms fitted to and adjustable on the index-bridge of a type-writing machine to ascertain the position of said type-aligner, substantially as specified.

15

In testimony whereof I affix my signature in presence of two witnesses.

CLEMENT SMITH.
